MACHINE FOR THE PRODUCTION OF
WIRE ROPES

Carl Julianus Holm, Trondheim, Norway

Application December 29, 1947, Serial No. 794,231

3 Claims. (Cl. 57—60)

1

In the production of wire ropes the individual wires are first twisted on a stranding machine to form strands and then the latter are twisted in a similar manner on a rope closing machine to form the finished wire rope.

The stranding and rope closing machines differ in dimensions only—the principle of operation and general construction being identical.

In the following specification and claims reference will be made to stranding machines and individual wires, but it will easily be understood that the invention applies equally well to rope-closing machines operating on the same principle.

In stranding and wire closing machines the bobbins carrying the individual wires or strands are generally mounted in forks pivoted on a frame rotating about a horizontal axis.

The wires including the central core are then conducted to the nose or head of the machine in which the twisting operation is performed and the finished strand is wound upon a bobbin rotating about a stationary axis.

Wire rope machines of this type have several drawbacks. First: The rotating frame carrying the wire bobbins has a great inertia which puts a definite limit to the speed of operation. Second: As it is practically impossible to mount the bobbins in the rotating frame without a certain amount of play, the bobbins will reciprocate in their bearings owing to the centrifugal action causing unavoidable wear of the parts involved as well as undesirable noise.

Further the substitution of new full bobbins for spent ones becomes a rather complicated job owing to the unbalanced condition of the frame during the changing process.

It is the object of the present invention to avoid these drawbacks and to provide a wire rope machine which adapted to operate silently at a high speed and in which the exchange of bobbins is simplified. The machine in accordance with the present invention also has the advantage of occupying far less floor space than the machines used up to the present time.

The main feature of the wire rope machine in accordance with the present invention consists in that the bobbins supplying the wires or strands are suspended in a substantially horizontal plane at a level above or below a twisting mechanism, performing the twisting of wires or strands about a substantially vertical axis.

In accordance with another feature of the invention the wire bobbins are rotatably suspended from the lower ends of rotating shafts the axes

of which remain stationary during the twisting operation.

A further feature of the invention consists in that the rotating shafts carrying the wire bobbins 5 being mounted in an annular frame which is adapted to be rotated about its axis for changing the position of the bobbin carrying shafts, means being provided for locking said annular frame in a stationary position during the twisting operation.

A still further feature of the invention consists in the axes of the bobbin carrying shafts converging downwardly towards an apex located on the axis of the twisting mechanism substantially at the point at which the twisting operation is performed.

The last named feature enables the wires to be conducted from the several bobbins to the nose or head of the machine without being exposed to bending stresses during their passage from bobbin to nose.

In order to make the invention clearly understood an embodiment of the same shall now be described with reference to the drawings which illustrate in a diagrammatical manner a stranding machine in accordance with the invention.

Fig. 1 is a vertical view of the machine with parts shown in section and Fig. 2 is a plan view of the bobbin frame.

The bobbin frame 1 is made in the form of a circular structure mounted on a circular rail or track 2 by means of rollers or wheels 3.

A braking or locking device 4 is provided for maintaining frame 1 in a stationary position during the wire rope production.

The wire bobbins 5 are rotatably mounted in forks (not shown) on the lower ends of shafts 6, which are again rotatably mounted in spaced relation along the circumference of frame 1. The axes of shafts 6 converge downwardly towards an apex located on the vertical axis of the frame. The bobbin 7 carrying the central core is suspended in a similar manner as wire bobbins 5 from a rotatably mounted central shaft 8.

Shafts 6 and 8 are rotated by means of belt drives 9, 10 so as to avoid twisting the wires or core about their own axes during the strand forming operation.

A stationary head or nose 11 is located approximately at the apex point towards which the axes of shafts 5 converge, said head or nose comprising suitable individual guides for the core and the wires.

From the head or nose 11 the core and the wires pass through the hollow shaft 12 of a frame

13 rotating about a vertical axis and having mounted herein the receiving bobbin 14 for the finished strand.

Conventional driving means (not shown) are provided for rotating frame 13 and bobbin 14 at correct relative speeds to obtain an uniform pitch during the twisting operation which takes place between the stationary head or nose 11 and rotating frame 13.

The substitution of full bobbins for spent ones in frame 1 may easily be carried out from a floor or platform (not shown) located a suitable distance below the frame and this operation is further simplified by releasing the frame so that it may be rotated by hand or otherwise in appropriate steps during the exchange which can then be carried out from one place below the circumference of the frame.

Although the invention has here been described in connection with a stranding machine, it will be easily understood that it may be applied in an identical manner to rope closing machines in which strands are used instead of individual wires.

Also it will be understood that although in the embodiment here described and illustrated the bobbin frame is located vertically above the rotating frame 13 and the twisting mechanism, the principle of the invention will not be changed if the whole machine be turned upside down so as to place the bobbin frame below the twisting mechanism.

I claim:

1. A machine for the production of wire ropes and the like comprising an open circular track having the axis thereof vertically disposed, a circular bobbin frame rotatably mounted on said track internally thereof, a plurality of spaced rotatably mounted shafts on said frame, said shafts being inclined with respect to and converging toward a common point on the vertical axis of said machine, bobbins rotatably mounted on an end of each said inclined shaft and arranged in a substantially horizontal plane, a central shaft on said frame vertically and rotatably mounted, the axis of said central shaft intersecting said common point of convergence of said bobbin

shafts, a core carrying bobbin rotatably mounted on an end of said last named shaft, a twisting mechanism mounted on the vertical axis of said machine and spaced from said bobbin frame, means for rotating said bobbin frame, and means for locking said frame in a stationary position during the twisting operation, wires being conducted from said bobbins to said twisting mechanism being substantially free from bending stresses due to the convergence of the bobbins.

2. A machine for the production of wire ropes and the like, as claimed in claim 1, said shafts being inclined inwardly towards the bottom thereof to a common point on the vertical axis of said machine below said shafts, said bobbins being rotatably mounted on the lower ends of said shafts, and said twisting mechanism being mounted below said bobbins on the vertical axis of said machine, said common point of convergence of said bobbin shafts being located substantially at the point where twisting of said wire rope is effected by said twisting mechanism.

3. A machine for the production of wire ropes and the like, as claimed in claim 1, said shafts being inclined inwardly towards the top thereof to a common point on the vertical axis of said machine above said shafts, said bobbins being rotatably mounted on the upper ends of said shafts, and said twisting mechanism being mounted above said bobbins on the vertical axis of said machine, said common point of convergence of said bobbin shafts being located substantially at the point where twisting of said wire rope is effected by said twisting mechanism.
